COMBINED REEL AND MOBILE STAND

Karl Johan Back and Ragnar Ilmari Olov Walhelin,
Helsinki, Finland, assignors to Oy Cyklop AB, Helsinki,
Finland

Filed Sept. 11, 1973, Ser. No. 396,180

Claims priority, application Finland Mar. 12, 1973

Term of patent 14 years

Int. Cl. D8—99; D12—02

U.S. Cl. D8—221

FIG. 2

FIG.1

FIG. 3

FIG. 1 is a front perspective view taken from the left side of a combined reel and mobile stand showing our new design;

FIG. 2 is a front perspective view taken from the right side thereof with the reel omitted;

FIG. 3 is an enlarged rear perspective view thereof with the reel in place.

We claim:

The ornamental design for a combined reel and mobile stand, as shown.
